UNITED STATES PATENT OFFICE.

HUGO LEONI, OF NEW YORK, N. Y., ASSIGNOR TO SUPER-RUBBER LINING CORPORATION, OF NEW YORK, N. Y., A CORPORATION OF NEW YORK.

NECKTIE AND LINING THEREFOR.

Application filed December 23, 1926. Serial No. 156,659.

This invention relates to linings for neckties and particularly to neckties of the four-in-hand type.

One of the principal objects of the present invention is to provide an improved resilient or elastic lining which is disposed within the body of the tie at and adjacent the knot forming portion of the longer outer lead of the tie and the shorter lead if desired.

More specifically the invention comprehends the provision of a resilient or elastic necktie lining which is freely stretchable laterally and which is provided with means for permitting of a limited longitudinal stretching.

The invention furthermore comprehends an elastic or resilient necktie lining which preferably is constructed of sheet rubber and in which side edges of the lining member are slitted to render the same more flexible when forming the knot without detracting from the resilient or elastic action to restore the body to its normal condition when the knot is untied.

Other objects reside in the simplicity and durability of the lining structure, the economy with which the same may be produced, and the general efficiency derived therefrom.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a view of a necktie equipped with a lining constructed in accordance with the invention;

Fig. 2 is an enlarged transverse sectional view therethrough taken approximately on the line indicated at 2—2 in Fig. 1;

Fig. 3 is an enlarged plan view of the lining member removed from the tie;

Fig. 4 is an edge view of the lining as illustrated in Fig. 3;

Fig. 5 is a plan view of a slightly modified adaptation of the invention;

Fig. 6 is an edge view thereof.

Referring to the drawings by characters of reference, the lining which is particularly

illustrated in Figs. 1 to 4, inclusive, is designed for the purpose of being initially incorporated with or made a part of the tie when the same is originally manufactured, whereas in Figs. 5 and 6, the lining is constructed to be sold separately from and applied to ties which have been previously purchased and which are not equipped with the improved lining, means being illustrated for readily connecting the improved lining with a tie structure.

In the form of the invention illustrated in Figs. 1 to 4, inclusive, 10 designates a non-elastic strip of material or tape which is designed to be incorporated and stitched into the neckband engaging portion 11 of the tie body, and said strip 10 has suitably attached to one end an elastic or resilient strip of material 12, which is preferably in the nature of sheet rubber and which is of a suitable configuration to conform to the shape of the tie body at and adjacent the knot-forming portion 13. At its free end the strip 12 has suitably attached thereto a non-elastic terminal piece 14. The material employed is essentially uncreasable and stretchable in all directions, which are the principal characteristics of sheet rubber of which the present invention makes use.

In order to limit the stretching or expansion of the strip 12 to the desired degree in the direction of the length of tie while allowing for free lateral expansion thereof, a non-elastic strip of material or tape 15 is attached at its opposite ends, respectively, to the member 10, and the terminal piece 14, with a limited amount of slack therein when the elastic strip 12 is normally contracted. The opposite side edges of the elastic strip 12 are formed with a plurality of slits 16 extending inwardly which function to allow for a greater flexibility of the lining and tie body when forming the knot, but which in no way detract from the inherent quality of the lining, which tends to restore itself and the tie body to normal shape.

In Figs. 1 to 4, inclusive, the non-elastic strip or member 10 is made of a sufficient length to extend completely through the neckband engaging portion 11 of the tie body and is adapted to be initially stitched or otherwise secured to the tie body when manufacturing the same, whereas in Figs. 5 and 6 the non-elastic strip or member 10 is

of considerably shorter length and is provided at its free end with a suitable clip 17 to facilitate the attachment of the lining member to the cut-off end of the ordinary lining of a tie. The lining member including the elastic or resilient strip 12^a, the non-elastic member 10^a and the non-elastic terminal element 14^a, together with the non-elastic terminal limiting member 15^a, is of identical construction to that described and shown in Figs. 1 to 4, inclusive, and functions in the same manner, the only difference being that in this form the lining member is intended to replace the ordinary tie lining which is cut-off at a point slightly beyond its protrusion from the neck-band engaging portion 11 and to which the replacement lining is attached either by stitching or by means of a clip or device of the type illustrated at 17 in Figs. 5 and 6.

What is claimed is:

1. A necktie including a body material, a strip of uncreasable elastic material stretchable in all directions and means allowing for and limiting the stretch of the same in the direction of the length of the tie.
2. A necktie lining including a strip of uncreasable elastic material stretchable in all directions, and means allowing for and limiting to a predetermined degree, the stretch of said strip of material in the direction of the length of the tie.
3. A necktie including a body material, a strip of uncreasable elastic material stretchable in all directions, attached at one end to the tie body substantially at the neck-band-engaging portion, said strip being free for lateral expansion, and means coacting with said strip to allow for and limit the longitudinal stretching thereof.
4. A necktie lining including a strip of uncreasable elastic material stretchable in all directions, attached at one end to the tie body substantially at the neckband-engaging portion, said strip being free for lateral expansion, and means coacting with said strip to allow for and limit the longitudinal stretching thereof to a predetermined degree.
5. A necktie lining including a strip of uncreasable elastic material stretchable in

all directions, attached at one end to the tie body substantially at the neckband-engaging portion, said strip being free for lateral expansion, and means coacting with said strip to allow for and limit the longitudinal stretching thereof, said means consisting of an inextensible element attached at its opposite ends to the opposite ends of said strip with a slack in said element when the said strip is in its normal longitudinally contracted condition.

6. A necktie lining, including a strip of uncreasable elastic material stretchable in all directions, unstretchable terminals carried by the opposite ends of said strip, and an inextensible connection between the terminals having a slack therein when the strip is in normal longitudinally contracted condition.

7. A necktie lining, including a strip of uncreasable elastic material stretchable in all directions, and means allowing for and limiting to a predetermined degree the stretch of said strip of material in the direction of the length of the tie, the side edges of said strip having slits for increasing the flexibility of the same without detracting from the elasticity thereof.

8. A necktie lining, including a strip of uncreasable elastic material stretchable in all directions, and means allowing for and limiting to a predetermined degree the stretch of said strip of material in the direction of the length of the tie, the side edges of said strip adjacent the knot-forming portion having slits for increasing the flexibility of the same without detracting from the elasticity thereof.

9. A necktie including a body material, a lining consisting of a strip of sheet rubber which is free to expand or contract laterally, and means allowing for and limiting the stretch of the same in the direction of the length of the tie.

10. A necktie lining, including a strip of sheet rubber, and means allowing for and limiting to a predetermined degree the stretch of the said strip of material in the direction of the length of the tie.

HUGO LEONI.
